UNITED STATES PATENT OFFICE

151,275

DESIGN FOR A POWER LAWN MOWER

Marlowe H. Kluter, Richmond, Ind., assignor to
The F. & N. Lawn Mower Company, Richmond,
Ind., a corporation of Delaware

Application October 30, 1946, Serial No. 134,376

Term of patent 14 years

(Cl. D40—1)

To all whom it may concern:

Be it known that I, Marlowe H. Kluter, a citizen of the United States of America, residing at Richmond, in the county of Wayne and State of Indiana, have invented a new, original, and ornamental Design for a Power Lawn Mower, of which the following is a specification, reference being had to the accompanying drawing, forming part thereof.

Figs. 1, 2 and 3 are a front elevation, perspective view, and side elevation, respectively, of a power lawn mower embodying my new design.

The characteristic features of the present design are shown in solid lines in the drawing.

I claim:

The ornamental design for a power lawn mower, substantially as shown and described.

MARLOWE H. KLUTER.
